UNITED STATES PATENT OFFICE

2,245,516

ELECTRICAL PRECIPITATOR

Harry A. Wintermute, Plainfield, N. J., assignor to
 Research Corporation, New York, N. Y., a corporation of New York

Application March 24, 1939, Serial No. 264,903

16 Claims. (CL 183-7)

This invention relates to the art of electric precipitation and is particularly directed to electrical precipitators of the wet type wherein a liquid is introduced into the gas to be treated in the form of a spray.

In the treatment of many gases in electrical precipitators, it is found desirable to introduce liquid spray into the gas stream shortly before the gas passes into the electric field between the discharge and collecting electrodes. The nature of the liquid used may vary with different types of gases and may consist of water, aqueous solutions or non-aqueous liquids such as oils. In many cases, the liquid apparently affects favorably the condition of the gas or of the deposited material, but regardless of the mode of action the beneficial effect of such liquid sprays in the industrial application of electrical precipitation to a number of gases is unquestionable.

However, when a liquid spray is introduced into the gas just prior to its passage into the electric field or directly into the electric field, the liquid particles of the spray tend to impinge on the discharge electrode system. The high voltage electric field causes this liquid to be discharged towards the opposing collecting electrodes. When the amount of liquid impinging on the discharge system is large or if the liquid collected on the discharge system is discharged from a few points, electrical breakdowns are caused even at voltages considerably below that at which breakdown normally occurs. Such breakdown necessitates operation at reduced voltages which in turn causes low corona discharge. This reduction in voltage and corona discharge causes poor removal of the suspended particles from the gas undergoing treatment.

These disadvantages are avoided in the present invention by providing a shield member positioned to prevent impingement of the spray upon the discharge electrodes.

A principal object of the invention, therefore, is to provide an electrical precipitator including means for introducing a finely divided liquid into the gas undergoing treatment and means for preventing impingement of the liquid upon the discharge electrodes.

The invention will be more particularly described with reference to the accompanying drawings illustrating representative embodiments of the principles of the invention:

In the drawings:

Fig. 1 is a sectional elevation of a horizontal flow electrical precipitator embodying the invention;

Fig. 2 is a transverse sectional elevation of the precipitator of Fig. 1;

Fig. 3 is a sectional elevation of a vertical flow precipitator embodying the invention;

Fig. 4 is a transverse sectional elevation of the precipitator of Fig. 3;

Fig. 5 is an elevation in partial section of a vertical flow pipe precipitator embodying the principles of the invention;

Fig. 6 is a sectional elevation on line 6-6 of Fig. 7 of an electrical precipitator with upwardly directed spray; and

Fig. 7 is a transverse sectional elevation on line 7-7 of Fig. 6.

15 In the embodiment of Figs. 1 and 2, the precipitator chamber comprises a body portion 10, having gas inlet and outlet openings 11 and 12, respectively, and a hopper bottom 13. Mounted within the body of the chamber are a plurality of plate collecting electrodes 14 in electrical connection with the grounded shell 10 and a plurality of discharge electrodes consisting of rods 15 bearing discharge attenuated or pointed discharge elements. The rods 15 are mounted 20 in parallel sets on members 16 which are carried on members 17 supported by rods 18 from insulating bushings 19, which pass through heated insulator compartments 20. The transverse members 16 are advantageously provided with 25 attenuated discharge elements, such as coiled wire 24, to prevent deposition of solid or liquid particles thereon.

30 Compartment 21 is furnished with a plurality of downwardly projecting spray nozzles 22 which supply a liquid spray to the space between the discharge and collecting electrodes. Mounted below the spray and extending above each parallel set of discharge electrodes are a plurality of shield members 23 which prevent direct 35 impingement of the spray on the members of the discharge electrode system, and direct the spray and coalesced liquid to points adjacent the collecting electrodes.

35 Discharge elements 24 eliminate any tendency for liquid dropping off the shields to be drawn in towards the high tension supporting members 16, by providing a discharge effective to drive the drip and spray toward the collecting electrodes.

40 Arch members 27 spanning the high tension electrode supports 16 between adjacent collecting electrodes tend to prevent undesirable arcing by providing a more uniform field distribution at the point where the high tension supports 45 pass out of the interelectrode space.

Perforated plates 25 at the gas inlet and outlet are provided for better distribution of the gas to the various portions of the precipitator and hopper baffle plate 26 is helpful in maintaining the distribution.

It will be seen that the apparatus of Figs. 1 and 2 provides means whereby a horizontally flowing stream of gas may be subjected to a high tension electric field between discharge and collecting electrodes while supplying a spray of liquid particles to said field without impingement of said particles on the discharge electrodes; and that it includes means providing a line or zone of corona discharge along the supporting members of the discharge electrode structure whereby attraction of liquid or solid particles to such members is prevented.

Figs. 3 and 4 illustrate an embodiment of the principles of the invention in a vertical flow precipitator. The precipitator comprises a rectangular shell 30 provided with a gas inlet or outlet 31 and gas outlet or inlet 32. Supported within the precipitator are a plurality of vertical collecting electrode plates 33 in electrical contact with the grounded shell and, between the collecting electrodes, a plurality of insulatedly supported discharge electrode rods 34 carried in parallel sets on members 35 supported on beams 36 which are supported by insulators 37 housed in heated insulator chambers 38, and are connected to a source of electric potential through one of the insulators 37. The supporting members 35 are provided with discharge elements 35a to prevent deposition of solid and liquid particles thereon as described with reference to Figs. 1 and 2.

Spray nozzles 39 are provided in the upper part of the precipitator. In this embodiment of the invention reservoirs 40, which provide liquid for flushing the collecting electrode surfaces, are so positioned above the discharge electrode assemblies as to shield the discharge electrode system from impingement of the spray. Manifolds 41 supply flushing liquid to the reservoirs, although they may be entirely supplied from the spray nozzles. The reservoirs preferably are provided with depending skirts 40a, which aid in securing a uniform flow of flushing liquid throughout the length of the collecting electrodes. It will be obvious that the roof-type shields of Figs. 1 and 2 can be used in the precipitator of Figs. 3 and 4, while the reservoir shields of the latter precipitator may be used in place of the roof-like shields in the precipitator of Figs. 1 and 2.

Hoppers 42 are preferably provided to conduct the sludge dropping from the bottom of the collecting electrodes to the lower part of the hopper at the bottom of the precipitator whence it flows out through sludge outlet 43.

The precipitator of Fig. 5 comprises a shell 50 having a gas inlet 51, gas outlet 52, and sludge outlet 53. Supported in the precipitator chamber by means of horizontal partition 54 are a plurality of pipe collecting electrodes 55. In the center of each pipe electrode is a rigid discharge electrode 56. The discharge electrodes are mounted on supporting members 57 which are suspended at each end from insulator bushings 58 in insulator housings 59. Sloping sleeves 60 which pitch toward the interior of the chamber prevent liquid from running along members 57 into the insulator housing.

In the upper portion of the precipitator chamber are a plurality of spray nozzles 61, which supply a mist of liquid particles to the gas stream

flowing into the electric field between the discharge and collecting electrodes. Suspended in the upper end of each collecting electrode pipe by spiders 62 are conical shields 63 which prevent impingement of the liquid particles on the discharge electrodes.

Discharge points 66a at the upper ends of the discharge electrodes serve the purpose of preventing drip from the shields from being pulled in toward the upper end of the electrode.

In the precipitator shown in Figs. 6 and 7, liquid spray is projected into the electric field between the discharge and collecting electrodes by means of paired rotating cylindrical members similar in principle of operation to the spray devices described in my copending application Serial No. 201,631, filed April 12, 1938.

The precipitator comprises a shell 70 having a gas inlet 71, gas outlet 72 and sludge outlet 73. Discharge electrode rods 74 are supported from members 75 mounted on member 76 carried on insulators 77.

Collecting electrode surfaces are provided by plates 78 and by the inner surfaces 79 of the shell.

Spray is projected into the interelectrode space by means of opposed cylindrical members 80 rotating in the direction indicated by the arrows, and dipping into a pool of liquid in reservoir 81. The spray is prevented from impinging on the discharge electrode system by shielding plates 82 positioned between the source of spray and the discharge electrodes.

It will be seen that the invention comprises a wide variety of means for providing a mist of liquid particles in the interelectrode space of an electrical precipitator while shielding the discharge electrode system from impingement of liquid particles.

I claim:

1. In apparatus for the electrical treatment of gas including opposed discharge and collecting electrodes, spray-producing means positioned to project a mist of liquid particles directly into the space between the discharge and collecting electrodes and shield members in electrical connection with the collecting electrodes and positioned between the source of liquid particles and the discharge electrodes to prevent impingement of the liquid particles on the discharge electrodes while permitting direct projection of mist into the inter-electrode space.

2. In apparatus for the electrical treatment of gas including opposed discharge and collecting electrodes, spray-producing means positioned to project a mist of liquid particles downwardly into the space between the discharge and collecting electrodes and shield members in electrical connection with the collecting electrodes positioned between the source of liquid particles and the discharge electrodes to prevent impingement of the liquid particles on the discharge electrodes.

3. In apparatus for the electrical treatment of gas including opposed discharge and collecting electrodes, spray-producing means positioned to project a mist of liquid particles upwardly directly into the space between the discharge and collecting electrodes and shield members positioned between the source of liquid particles and the discharge electrodes to prevent impingement of the liquid particles on the discharge electrodes while permitting direct projection of mist into the inter-electrode space.

4. An electrical precipitator comprising means defining a chamber, means providing an inlet

for gas into said chamber and an outlet for gas out of said chamber, opposed discharge and collecting electrode members in said chamber, spray devices positioned to project a mist of liquid particles directly into the space between the discharge and collecting electrodes, and shield members in electrical connection with the collecting electrode system and positioned to prevent impingement of the liquid particles on the discharge electrodes while permitting direct projection of mist into the inter-electrode space.

5. An electrical precipitator comprising means defining a chamber, opposed discharge and collecting electrode members in said chamber, means providing a passage for gas through said chamber between the discharge and collecting electrode members, spray devices positioned to project a mist of liquid particles directly into the space between the discharge and collecting electrodes, and shield members in electrical connection with the collecting electrode system and positioned to prevent impingement of the liquid particles on the discharge electrodes while permitting direct projection of mist into the inter-electrode space.

6. An electrical precipitator comprising means defining a chamber, opposed discharge and collecting electrode members in said chamber, means providing a passage for gas through said chamber between the discharge and collecting electrode members, spray devices positioned in the gas stream to project a mist of liquid particles directly into the space between the discharge and collecting electrodes, and shield members in electrical connection with the collecting electrode system and positioned to prevent impingement of the liquid particles on the discharge electrodes while permitting direct projection of mist into the inter-electrode space.

7. An electrical precipitator comprising means defining a chamber, opposed discharge and collecting electrode members in said chamber, means providing a passage for gas through said chamber between the discharge and collecting electrode members, spray devices positioned above the discharge and collecting electrodes to project a mist of liquid particles into the space between the discharge and collecting electrodes, and shield members in electrical connection with the collecting electrode system and positioned to prevent impingement of the liquid particles on the discharge electrodes.

8. An electrical precipitator comprising means defining a chamber, opposed discharge and collecting electrode members in said chamber, means providing a passage for gas through said chamber between the discharge and collecting electrode members, spray devices positioned below the discharge and collecting electrodes to project a mist of liquid particles directly into the space between the discharge and collecting electrodes, and shield members in electrical connection with the collecting electrode system and positioned to prevent impingement of the liquid particles on the discharge electrodes while permitting direct projection of mist into the inter-electrode space.

9. In apparatus for the electrical treatment of gas including opposed discharge and collecting electrodes, means for introducing a mist of liquid particles directly into the space between the discharge and collecting electrodes and shield members positioned within the space defined by the collecting electrodes to prevent impingement of the liquid particles on the discharge electrodes

while permitting direct projection of mist into the inter-electrode space.

10. In apparatus for the electrical treatment of gas including opposed discharge and collecting electrodes, means for introducing a mist of liquid particles directly into the space between the discharge and collecting electrodes and shield members positioned within the space defined by the collecting electrodes and between the source of liquid particles and the discharge electrodes to prevent impingement of the liquid particles on the discharge electrodes while permitting direct projection of mist into the inter-electrode space.

11. In apparatus for the electrical treatment of gas including opposed discharge and collecting electrodes, means for introducing a mist of liquid particles downwardly into the space between the discharge and collecting electrodes and shield members positioned between the source of liquid particles and the discharge electrodes to prevent impingement of the liquid particles on the discharge electrodes, said shield members comprising liquid collecting reservoirs providing a substantially uniform supply of liquid to said collecting electrodes.

12. In apparatus for the electrical treatment of gas including opposed discharge and collecting electrodes, means for introducing a mist of liquid particles downwardly into the space between the discharge and collecting electrodes and shield members positioned between the source of liquid particles and the discharge electrodes to prevent impingement of the liquid particles on the discharge electrodes, said shield members comprising liquid collecting reservoirs having downwardly depending skirt members providing a substantially uniform supply of liquid to said collecting electrodes.

13. In apparatus for the electrical treatment of gas including opposed discharge and collecting electrodes, means for introducing a mist of liquid particles into the space between the discharge and collecting electrodes, shield members positioned between the source of liquid particles and the discharge electrodes to prevent impingement of the liquid particles on the discharge electrodes, and discharge producing elements positioned between said shield members and said discharge electrodes to prevent drip from the shields from being attracted to the discharge electrodes.

14. In an electrical precipitator, a chamber having a gas inlet and a gas outlet, two collecting electrodes mounted in said chamber to define a gas passage therebetween, an insulated high tension member supporting and positioning at least one discharge electrode in said passage, spray-producing means positioned to project a mist of liquid particles into the space between the discharge and collecting electrodes, said high tension member being positioned between the discharge electrode supported thereby and the spray-producing means, and shield members positioned between said spray-producing means and said high tension member.

15. In an electrical precipitator, a chamber having a gas inlet and a gas outlet, two collecting electrodes mounted in said chamber to define a gas passage therebetween, an insulated high tension member supporting and positioning at least one discharge electrode in said passage, spray-producing means positioned to project a mist of liquid particles into the space between the discharge and collecting electrodes, said high tension member being positioned between the discharge electrode supported thereby and the spray-producing means.

70 75

ducing means, and shield members electrically connected to the collecting electrodes positioned between said spray-producing means and said high tension member.

16. In apparatus for the electrical treatment of gas including opposed discharge and collecting electrodes, spray-producing means positioned to project a mist of liquid particles into the space between the discharge and collecting electrodes,

5 shield members positioned between the source of liquid particles and the discharge electrodes to prevent impingement of the liquid particles on the discharge electrodes, and discharge producing elements connected to said discharge electrodes and opposing said shield members to prevent drip from the shields from being attracted to the discharge electrodes.

HARRY A. WINTERMUTE.

CERTIFICATE OF CORRECTION.

Patent No. 2,245,516.

June 10, 1941.

HARRY A. WINTERMUTE.

It is hereby certified that error appears in the printed specification of the above numbered patent requiring correction as follows: Page 3, first column, line 70, and second column, lines 5, 16, 28 and 41, claims 9, 10, 11, 12 and 13 respectively, for the words "means for introducing" read --spray-producing means positioned to project--; and that the said Letters Patent should be read with this correction therein that the same may conform to the record of the case in the Patent Office.

Signed and sealed this 8th day of July, A. D. 1941.

(Seal)

Henry Van Arsdale,
Acting Commissioner of Patents.
